5, 1948, Serial No. 6,486

2 Claims. (Cl. 22—58.5)

1

This invention relates to the molders art and is particularly useful in casting tubular structures.

It is an object of this invention to provide a novel and efficient apparatus for casting tubular structures.

Another object of the invention is to provide such an apparatus which is particularly adaptable for providing tubular linings within tubular shells.

Yet another object of the invention is to provide such an apparatus by which Venturi tube shells may be efficiently provided with cast metal linings requiring a minimum of machine work to produce a finished article.

Yet another object of the invention is to provide a molding apparatus in which a cooling medium may be applied to a core of the mold internally without substantial danger of this medium being admitted into contact with the molten metal in the mold, and while said mold is being whirled about an axis disposed transversely to and intersecting the longitudinal axis of the mold.

This application is a division of our co-pending application for U. S. Letters Patent, Serial No. 621,906, filed October 12, 1945, and now issued as U. S. Letters Patent No. 2,445,364.

The manner of accomplishing the foregoing objects, as well as further objects and advantages, will be made manifest in the following description taken in connection with the accompanying drawings in which:

Fig. 1 is a plan view of a preferred embodiment of the apparatus of the invention.

Fig. 2 is a front elevational view of Fig. 1, partly broken away to disclose hidden portions of the apparatus, a portion of the apparatus shown in Fig. 2 being diagrammatically disclosed.

Fig. 3 is an enlarged diagrammatic sectional view.

Fig. 4 is a cross sectional view taken on the line 4—4 of Fig. 3.

Fig. 5 is a fragmentary side elevational view of the shiftable head end of the chuck of the invention illustrating how this is shifted when introducing a mold into the chuck and when removing a mold therefrom.

Fig. 6 is an end elevational view taken in the direction of the arrow 6 in Fig. 5.

Fig. 7 is a longitudinal sectional view of a lined Venturi tube as this comes from the apparatus of our invention and before it has been finished.

Fig. 8 is a fragmentary view of the right-hand

2

end of the Venturi tube shown in Fig. 7 as this appears after the final finishing step which follows removal of said Venturi tube from the apparatus.

5 Referring specifically to the drawings, the molding apparatus therein disclosed is indicated generally by the numeral 10. This includes a table 11 having legs 12 joined by a lower plate 13 and by a table top 14, the latter being surrounded by a wall 15. Swingably mounted on the left front corner of the wall 15 is a gas torch 16 and on the opposite front corner is swingably mounted a ladle rest 17. The plate 13 is provided with a central bearing 20 while 10 the table top 14 has a central bearing 21 aligned vertically therewith. Mounted on the left side of the table 11 is an electric motor 22 which is connected by a belt 23 with a pulley 24 provided on a hollow shaft 25, upper and lower ends of 15 which journal in the bearings 21 and 20 respectively.

The upper end of the hollow shaft 25 has a shoulder 26 which fits within the inner race of the bearing 21 and a heavy flange 27 which 20 overlies said bearing. The bore 28 of the shaft 25 is of uniform diameter and extends throughout the length of the shaft 25 and upwardly through the shoulder 26 and flange 27. Provided in the flange 27 and leading from the bore 28 is a radial passage 29. Resting on the flange 27 is a heavy cap plate 30 having a passage 31 which connects with the upper end of the bore 28 and extends radially to the periphery of the cap plate 30. Screwed into threaded outer 25 ends of the passages 21 and 31 are tubing connection nipples 32 and 33.

Resting on the plate 30 is an apron disc 38 and a mold chuck 40, the latter having a base plate 41 which rests on top of the disc 38 and is secured to the flange 27 by cap screws 42 which 30 extend downwardly through the base plate 41, the disc 38, and the cap plate 30 and are screwed into suitable threaded holes provided in the flange 27.

45 Welded to opposite edges of the base plate 41 is a pair of parallel chuck frame bars 43. Resting between and welded to opposite ends of these bars is a metal block 44 and a fixed chuck head 45. Provided in the block 44 is a horizontal bore 46 in which is slideably received a shaft 47, opposite ends of which are threaded. The outer end of shaft 47 receives lock nuts 48 and the inner end is screwed into a threaded hole provided in a shiftable chuck head 49.

50 The block 44 also has four holes 50, opposite

which corresponding holes 51 are provided in the shiftable chuck 49. These two sets of holes are occupied by coiled expansion springs 52 so as to constantly urge the head 49 away from the block 44. The lock nuts 48 operate as a stop to limit the response of the shiftable chuck 49 to the springs 52.

The chuck 49 has an inner face 55 which is recessed to receive an annular packing 56 which is co-axial with the shaft 47. Also formed in the chuck 49 and opening centrally in the face 55 is a passage 57 which turns downwardly to threadedly receive an elbow tubing nipple 58 at its lower end. Tubing nipples 33 and 58 are connected by a relatively flexible metal tube 59.

Formed on and extending laterally from the shiftable chuck 49 are studs 60. Similar studs 61 are provided on and extend outwardly from adjacent ends of the bars 43.

The fixed chuck head 45 is disposed co-axially with the shiftable chuck head 49 and has an inner face 65 which is recessed to receive an annular packing 66. The head 45 has an axial passage 67, the outer end of which is threaded, and has an elbow tubing nipple 68 screwed therein. The passage 67 has an inner counter-bore 69 in which a short expansion spring 70 is mounted. Connecting the nipple 68 with the nipple 32 is a metal tubing 71.

The chuck 40 is adapted to be actuated by a toggle wrench 75 comprising a handle 76 which is bifurcated to provide arms 77 having notches 78 at their extremities and to which is pivotally connected a yoke 79 formed of two hooks 80 and a connecting band 81.

The manner of using the toggle wrench 75 is illustrated in Fig. 5. Here it is seen that the yoke 79 is allowed to come to rest on the shiftable chuck head 49 so that the hooks 80 engage the studs 60. The handle 76 is now manipulated to bring the studs 61 within the notches 78. The handle 76 is now pressed down to swing this into its broken line position in Fig. 5. This collapses the springs 52 and shifts the chuck head 49 towards the stationary block 44. The chuck heads 45 and 49 are thus separated to permit the insertion of a mold 85 between these heads.

As the apparatus 10 is especially useful in casting liners in Venturi tube shells, the mold 85 is shown as including such a shell 86. This shell has a typical long tapering bore 87 with a short outwardly flaring mouth 88 at the narrow end of the bore 87. The shell 86 is provided with a gate or pouring hole 89 which is disposed approximately midway between its opposite ends and when the shell is assembled in the mold 85 and the latter held in the chuck 40, this hole is disposed coaxially with the hollow shaft 25.

The mold 85 also includes a core 90 comprising a long tapering core element 91 and a short tapering core element 92 which slips over the small end of the core element 91 and into the flared mouth 88 of the bore 87 of the Venturi tube shell 86 when the element 91 is inserted into this bore from the opposite end thereof. The core element 91 has a hole 93 disposed axially therein and extending throughout its length. The core element 92 has a bore 94 which snugly receives the small end of the element 91 and is counterbored to receive a packing ring 95 and a packing follower 96 which is adapted to be pressurably contacted by the spring 70 when the mold 85 is placed in the chuck 40. The core element 91 has permanently secured thereto a sleeve 97 which is adapted to slip over and be

secured to one end of the shell 86 by a set screw 98. This sleeve has an annular bead 99 which is adapted to engage the packing ring 56 to form a tight seal when the mold 85 is placed in the chuck 40.

The core element 92 is provided with an annular sleeve 100 which is adapted to slip over and be secured to the shell 86 by a set screw 101. This sleeve has an annular bead 102 which is adapted to press against and make a sealing engagement with the packing ring 66 when the mold 85 is placed in the chuck 40.

From the description of the mold 85, it is seen that the assembly of the parts thereof provides a mold chamber 110 with which the pouring gate 89 communicates. It is also seen that the seals effected by the packing rings 56 and 66 provide a practically fluid tight connection between the core passage 93 and the passages 57 and 67 in the chuck heads 45 and 49. In a manner which will be made clear hereinafter, this connection facilitates the application of a cooling medium internally to the core 90.

The bearing 20 has a downward tubular extension 115, the lower end of which is threaded to receive an adapter 116. Provided in the tube 115 is a threaded hole 117 into which a pipe 118 is screwed. (Fig. 2.) This pipe leads to a water supply tank 119 which is kept filled with water, by a float control valve 121, up to a level 120 (which is just below the level of the axis of the mold 85 when held in the chuck 40). Screwed into the threaded opening 122 of the adapter 116 is a three-way fitting 123 which connects with a tube 124 terminating in a vacuum gauge 125 and with a pipe 126 which leads to the suction end of an ejector 127. The ejector 127 is operated by air supplied thereto under high pressure from a pipe 128 which is controlled by a valve 129.

Pressed into the lower end of the hollow shaft 25 is a tube 140 having holes 141 formed therein opposite the hole 117 in the tube 115. Surrounding the tube 140 and pressed into the lower end of the tube 115 is a sleeve 142 having packing rings 143 on its opposite ends which seal off the space around the tube 140 between these rings. The sleeve 142 has a hole 144 which communicates between this space and the threaded hole 117.

Disposed axially in and extending throughout the combined length of the hollow shaft 25 and lower tubular extension 140 thereof is a small diameter tube 150, this being held in place at its upper and lower ends by packing rings 151 and 152 which seal off the space in the shaft 25 and tube 140 surrounding the central tube 150.

Operation

The manner in which the apparatus 10 of our invention is preferably employed is as follows: A considerable number of the mold cores 90 are provided and these are assembled with Venturi tube shells 86 and heated in an oven to approximately the melting temperature of the metal with which liners for the shells 86 are to be cast. This metal may be of any type suitable for die-casting work but preferably is babbitt. When a lot of molds 85 have thus been assembled and heated and one of these has arrived at the proper temperature, it is picked up by a pair of tongs and the toggle wrench 75 applied, as shown in Fig. 5, to retract the shiftable chuck head 49 and permit the hot mold 85 to be placed between this chuck head and

the fixed head 45 and in axial alignment with these. The toggle wrench 75 is then released and removed to allow the springs 52 to press the mold 85 between the chuck heads 45 and 49. When this is done, the seals above described are effected by the packing rings 56, 66 and 95.

The motor 22 is now energized to rotate the chuck 40 and the mold 85 mounted therein about the axis of the mold gate 89. The torch 16 is then lighted and swung inwardly as shown in Fig. 1 to bear directly on the shell 86 adjacent the hole 89. The ladle rest 17 is also swung towards the center of the apparatus as shown in Fig. 1 and a ladle L containing molten metal is placed across the rest 17 as shown in Fig. 2 and metal poured therefrom through the mold gate 89 until the mold chamber 110 is filled. The air valve 129 is now opened so that flow of this through the ejector 127 imposes a suction on the pipe 126 which is transmitted through the small tube 150, passage 31, tube 59, nipple 58 and passage 57 to the axial cooling fluid passage 93 in the core element 91. As water seeks its own level, water will flow from the tank 119 to the pipe 118 through the holes 144 and 141 into the tube 140 and hollow shaft 25 and out of the upper end of this into passage 29, nipple 32 and tube 71. As soon as a suction is imposed, as noted, upon one end of the cooling fluid passage 93 in the core element 91, a supply of water is readily available to the opposite end of this tube. Water is thus sucked into the passage 91 and of course is converted immediately into steam. This is withdrawn from the case by the suction imposed thereon and the steam is drawn downwardly into the central tube 150 which is kept cool by the surrounding water thereby condensing the steam and creating a vacuum which accelerates the removal of the steam from the central core passage 93.

The water thus admitted to the passage 91 rapidly cools the core 90 causing the molten metal in the mold chamber 110 to contract and the operator continues to pour metal from the ladle L into the hole 89 until the metal in this hole congeals.

The manner of introduction of the cooling medium into the core 90, that is by suction, eliminates the possibility of this cooling medium being forced into the mold chamber 110 where it would contact the molten metal and cause an explosion.

When the metal in the gate 89 has congealed, the valve 129 is closed, the torch 16 and ladle rest 17 are swung out of the way and the motor 29 is de-energized. The motor is preferably equipped with an automatic brake which sets itself when the motor is shut off to quickly automatically bring the revolving chuck 40 to a standstill.

The wrench 75 is again applied as shown in Fig. 5 and the chuck heads 49 and 45 separated to permit the mold 85 to be removed by a pair of tongs applied thereto. This mold is now placed in an arbor puller and after the set screws 98 and 101 have been loosened, the core elements 91 and 92 are pulled from opposite ends of the liner 165 which has just been cast in the Venturi tube shell 86. This leaves the product, a completed Venturi tube 166, as shown in Fig. 7, free from the core elements of the mold and ready for the final finishing step. This con-

sists in removing the annular fin 167 occurring at the juncture of the core elements 91 and 92 by a machining operation which leaves the throat 168 of the Venturi tube 166 as shown in Fig. 8.

The performance of our invention may be repeated with the apparatus 10 as many times as desired in precisely the manner described. From this it may be readily seen that with our invention, Venturi tubes 166 may be provided with suitable tubular linings rapidly and at relatively low cost.

It is also to be understood that while our invention is especially adapted for providing linings in Venturi tubes, it is not limited to this use and may be employed for casting tubular linings in tubular shells generally.

This application is a division of the application which matured into U. S. Letters Patent No. 2,445,364.

We claim:

1. In a casting apparatus the combination of: a mold having chucking ends and being provided with a mold cavity, the latter having a pouring gate opening thereinto, said mold also being provided with a cooling hole extending therethrough from one chucking end thereof to the other without opening into said mold cavity or said gate; a base; a pair of aligned chucks mounted on said base, one of said chucks being shiftable relative to the other to clamp said mold between said chucks with the latter pressed against said chucking ends of said mold, there being a cooling medium passage in each of said chucks which communicates with the adjacent end of the aforesaid cooling hole when said mold is so clamped; and seals compressible between said mold and said chucks for making fluid tight connections between said hole and said passages when said mold is so clamped.

2. A combination as in claim 1 in which said base and mold and said cooling hole are horizontal, and which includes a hollow vertical shaft on which said base is mounted; means for rapidly rotating said shaft, base, chucks, and mold; and means for circulating a cooling medium through said shaft and said base to and from said chuck passages to produce a flow of said medium through said cooling hole in said mold during said rotation.

DAN R. RANKIN.
